Inventor:
Wm M. Garee.

UNITED STATES PATENT OFFICE.

WILLIAM M. GAREE, OF GRANVILLE, OHIO.

IMPROVEMENT IN CORN-PLANTERS.

Specification forming part of Letters Patent No. 27,358, dated March 6, 1860.

To all whom it may concern:

Be it known that I, WILLIAM M. GAREE, of Granville, in the county of Licking and State of Ohio, have invented a new and useful Machine for Planting Corn and other Seeds; and I do hereby declare that the following is a full, clear, and exact description of the construction and operation of the same, reference being had to the annexed drawings, making a part of this specification, in which

Figure 1 is a perspective view; Fig. 2, a longitudinal view with the side taken off to show the parts and attachments. Fig. 3 is an enlarged view of the brush-block. Fig. 4 is a perspective view of the seed-slide or charger. Fig. 5 is the ear by which the seed-slide or charger is attached to the lever-upright. Fig. 6 is an edge view of the lever and hinge uprights, showing their relation, parts, and attachments. Fig. 7 is an outside view of the stationary upright, showing the attachment of its steel bit or jaw, and the position of the mortise and slit in which the seed-slide or charger and its flange moves. Fig. 8 is a block with a groove in which the seed-slide moves and is guided. Fig. 9 is a wedge-shaped block placed permanently between uprights Nos. 1 and 2, just below the hinge.

a a a (marked also 1 2 3) are uprights or frame-pieces. No. 1 is the lever-upright, because its vibration moves the jaw at the lower end of the machine. No. 2 is called the "middle" or "jointed" upright, because on it is placed the hinge *i*, to enable the lever-upright easily to move the bit or jaw. No. 3 is called the "stationary upright" because it is attached permanently to the hopper, charger-block, lid, and part of upright No. 2.

b b are steel bits or jaws formed or bent to about the angle of fifteen degrees, and strongly secured by rivets (see Fig. 7) to the bottoms of uprights Nos. 2 and 3.

c is a flange with a curved end, and placed on the seed-slide or charger to break the arch liable to be formed by the seed when the machine is in operation and prevent the charging or filling of the seed-chamber.

d is an ear having an oblong hole, and secured by a screw to upright No. 1, and to it is attached, by a pin working loosely in its openings, the seed-slide or charger. This device secures a seeming vibration of the pin, and thoroughly prevents the impinging and chaf-

ing of the seed-slide or charger in its movements.

e is a brush-block placed in the hopper to hold the bristles that brush back the seed of the hopper at every discharge of the seed-slide, protects the seed from injury by the chafing of the graduating-slide of the charger, and covers the opening where the charger conveys its seed to the chamber *l l* as a portion deposited for each hill.

f are the bristles (see Fig. 3) forming the brush, and secured in their place by gluing and the iron plate *n*, which is fastened by screws.

g is a block with a groove, *z*, Fig. 8, in which the seed-slide or charger is placed, and moves loosely, and in it also is a gain or mortise, &, through which the seed passes to the chambers *l l*.

h is a guard made of hoop or sheet iron, about one-sixteenth of an inch in thickness, placed over the bottom or lower end of the chamber *l l*, so as to cover the edges of the uprights 2 and 3 from a point three-eighths of an inch above the center of the hinge to their termination at the angle of the bits or jaws *b b* and exclude the earth.

i is a hinge connecting the two parts of upright No. 2, and providing for the vibration of the upright No. 1.

j j are two handles, by means of which the machine is put in operation.

k k are collars or bosses, round or angular, placed on the top ends of uprights 1 and 3, where the handles *j j* pass through to give them strength and permanence.

l l is a hopper or seed-box, formed by inclosing the space between the uprights 2 and 3, at the top, with sheet-iron or any other suitable material, and secured there by screws or tacks.

l l is a chamber that receives the seed from the charger *m*, and is formed by continuing downward the sheet-iron or other material used for hopper *l l*. This arrangement confines the seed for each hill successively.

m is a seed-slide or charger, Fig. 4, attached to ear *d* on upright No. 1, which receives the seed from the hopper *l l* and carries it under the brush-block *e* and discharges it into the chamber *l l*.

n is an iron plate screwed on the brush-block *e* to cover and confine the bristles at the top. (See Fig. 3 at *n*.)

o is a wedge-shaped block of wood, Fig. 9,

placed between uprights 1 and 2, just below the hinge *i*, (connecting the parts of upright No. 2,) to give strength and permanence to their connection.

p is a lid, Fig. 2, made of sheet-iron or other material, attached to upright No. 3 by a hinge, *r*, and covers the hopper.

q is a staple placed in the top of upright No. 2, and passes through the lid *p*, which it secures in its place by a hooked latch or pin. (See Fig. 1.)

r, Fig. 2, is a hinge to the hopper-lid *p*.

s, Fig. 4, is a chamber in the seed-slide or charger, which receives the seed from the hopper *t* and conveys it to the chamber *ll*, ready for each hill.

The operation of the machine is as follows: The hopper *t* having been filled with corn, and the handles *j j* being extended, the operator closes the handles, which movement fills the charger. The handles are then opened, by

which the seed contained in the charger is caused to fall into the chamber *ll*. At the same time the jaws at the bottom are tightly closed and ready for entrance into the earth. The jaws are then thrust into the earth and the handles closed, by which movement the seed in chamber *ll* is allowed to fall into the earth and the charger is again filled. The machine is then withdrawn from the earth, and the operation repeated in the manner stated for each hill.

Having thus described my invention, I claim and desire to secure by Letters Patent—

The arrangement of the flange *c*, seed-slide or charger *m*, plate *n*, brush-block *e*, chamber *ll*, uprights 1 2 3, lid *p*, and jaws *b b*, as and for the purposes herein shown and described.

WM. M. GAREE.

In presence of—

JOHN F. FOLLETT,
WM. BELL, Jr.
